UNITED STATES PATENT OFFICE

SAMUEL W. STROUSE, OF ST. JOHNS, MICHIGAN

DESIGN FOR A TOY BLOCK

Application filed April 15, 1929. Serial No. 30,910. Term of patent 14 years.

To all whom it may concern:

Be it known that I, SAMUEL W. STROUSE, a citizen of the United States, residing at St. Johns, in the county of Clinton and State of Michigan, have invented a new, original, and ornamental Design for Toy Blocks, of which the following is a specification, reference being had to the accompanying drawing, forming part thereof.

I claim:—

The ornamental design for a toy block, as shown.

SAMUEL W. STROUSE.
